UNITED STATES PATENT OFFICE.

JOHN R. CHRYSST, OF TACOMA, WASHINGTON.

DESIGN FOR AN ELECTRIC HEATER.

Application filed October 5, 1926. Serial No. 18,248. Term of patent 8½ years.

To all whom it may concern:

Be it known that I, JOHN R. CHRYSST, a citizen of the United States, residing at Tacoma, in the county of Pierce, State of Washington, have invented a new, original, and ornamental Design for Electric Heater, of which the following is a specification, reference being had to the accompanying drawing, forming part thereof.

Fig. 1 is a perspective view of an electric heater constructed according to the present design.

Fig. 2 is a front view of the same.

Fig. 3 is an end view.

I claim:

The ornamental design for an electric heater as shown.

JOHN R. CHRYSST.
